COPYING MACHINE

Mark Herschel Taylor, Leicester, England, assignor to Kapella Limited, Leicester, England, a company of Great Britain

Application July 21, 1938, Serial No. 220,465.
In Great Britain July 24, 1937

24 Claims. (Cl. 90—13.1)

This invention relates to copying machines of the kind in which a tool is caused to produce on the work a reproduction of the outlines of a copy such as a drawing or template. The nature of the tool will depend on the operation to be performed on the work, and the tool may consist, for example, of an abrasive wheel or an end mill for grinding or cutting the work or of a stylus or other marking device for imparting surface markings to the work.

Existing machines of this kind usually employ a tracer for following the outlines of the copy and a pantograph or other suitable mechanism for interconnecting the tracer, the copy, the tool and the work in such a manner as to produce relative movement between the tool and the work, which is a scale reproduction of the relative movement between the tracer and the copy. Such machines can be so designed as to give a high degree of accuracy in the reproduction provided that the reproduction ratio is fixed, but mechanical errors and inaccuracies are inevitably introduced if the inter-connecting mechanism is made adjustable to give a variable reproduction ratio. Moreover the use of a fixed high ratio, although of course giving greater accuracy than a low ratio, is inconvenient since it involves either the use of a very large and expensive machine which is inconvenient to operate or the restriction of the work operated on to very small dimensions. In practice it is amply sufficient in a large number of instances to operate with a fixed ratio of, say, 5:1, but it is often required in individual instances to use a much higher ratio.

Such difficulty is avoided in a machine according to the specification of the present applicant's patent application Serial No. 151,891, dated July 3, 1937, which comprises an optical system for forming an image of the drawing or other copy, whose outlines are to be reproduced on the work, a sighting device for viewing such image, means for imparting relative movement to the image and the sighting device whereby the sighting device can be caused to trace the outlines of the image, and means whereby such relative movement is caused to control relative movement between supports for the tool and the work. The preferred construction of machine described and illustrated in the said specification employs a fixed ratio pantograph for producing relative movement between the tool and work supports which is a scale reproduction of the relative movement between two further supports, which may carry, as may be desired, either a

tracer and copy for direct mechanical reproduction at the fixed pantograph ratio after the manner of the known machines, or the image and the sighting device for indirect mechanical and optical reproduction at a ratio determined by the product of the pantograph ratio and the optical magnification ratio.

Such a machine, however, in common with the prior known machines, calls for highly skilled workmanship in manufacture and also for the use of specially designed parts, such as bearings, in order to enable the desired high degree of accuracy to be obtained in the operation of the pantograph or other interconnecting mechanism for producing the mechanical scale reproduction.

In the machine according to the present invention the reproduction ratio of the machine is determined wholly in accordance with the optical magnification ratio without any mechanical scale reproduction, by maintaining the relative movement between the tool and work supports equal to that between the image and the sighting device.

For the purpose of operating on the work the tool may have rotary or reciprocating or rotary and reciprocating movement relative to the work, such movement being independent of and superimposed on the relative movement controlled by the relative movement of the image and sighting device.

The image and the sighting device may be directly carried one by each of the supports for the tool and the work so as to move therewith, or alternatively supports for the four elements may be interconnected by mechanism operating at unity gear ratio. Thus the four supports may have datum points or origins, two of which have normally fixed operative positions, whilst the other two are constrained to move so that the line joining them remains parallel and equal to the line joining the first two. Conveniently two of the four supports (preferably the two movable supports) are synchronously rotatable about parallel axes passing through their datum points or origins. Thus these two supports may be mounted in bearings in a member which can move, for example under the control of two mutually perpendicular slideways, in such a manner as always to remain parallel to itself. It will usually be more convenient for the work and image supports to constitute the two rotatable supports.

Means are preferably provided for varying the optical magnification ratio. This can conveniently be achieved by so mounting the optical sys-

tem and the copy that they can be adjusted along the optical axis of the system.

Means may also be provided whereby the tool can be constrained to generate straight lines and 5 circular arcs on the work in accordance with basic measurements.

The invention may be carried into practice in various ways but one construction, together with some modifications, is illustrated by way of example in the accompanying drawings, in which:

Figure 1 shows the apparatus in side elevation.
Figure 2 is a view from right to left of Figure 1.

Figure 3 shows the apparatus in vertical section,

Figure 4 is a section on an enlarged scale, showing the manner in which current is supplied for illuminating the copy.

Figure 5 illustrates, in section, a modified arrangement for illuminating the copy,

Figures 6 and 7 show in side elevation and plan respectively one way in which the apparatus may be modified for circular arc grinding.

Figure 8 illustrates a modified construction,

Figures 9 and 10 show in plan and side elevation respectively an arrangement employing pivoted links, instead of mutually perpendicular slideways, for controlling the movements of the carriage.

Referring more particularly to Figures 1 to 4 of the drawings, the machine comprises a fixed base A provided with ball tracks A¹ extending transverse to the length of the base A and carrying 35 operating with balls A² which engage transverse tracks B¹, carried by a slide B. The tracks A¹, B¹ and the balls A² thus constitute a slideway along which the slide B can move transversely to the length of the base A. The slide B is furnished 40 with ball tracks B² at right angles to the tracks A¹, B¹ and engaged by balls B³ which also co-operate with tracks C¹ carried beneath a carriage C, the tracks B², C¹ and balls B³ thus constituting a second slideway along which the 45 carriage C can move in the direction of the length of the base A, i. e., in a direction at right angles to the movement of the slide B.

The transverse adjustment of the slide B is effected by manual rotation of a head D (Figures 50 1 and 2) in screwthreaded engagement with a thrust rod D¹ and bearing against an abutment nut D² so that rotation of the head D causes longitudinal movement of the rod D¹. The inner end of the rod D¹ bears against a lug on the slide B, tension springs D³ acting between the slide B and a fixed part of the base so as to maintain the slide B firmly in engagement with the inner end of the rod D¹. The abutment nut D² is split as shown in Figure 1 and is in 55 sliding engagement with a pin D⁴ carried by the base A, the nut D² being normally locked to the pin D⁴ by an eye bolt D⁵ and cooperating finger screw D⁶.

The longitudinal adjustment of the carrier C is effected by manual rotation of a head E in screwthreaded engagement with a thrust rod E¹ and bearing against an abutment nut E² so that rotation of the head E causes longitudinal movement of the rod E¹. The inner end of the rod E¹ bears against a lug on the carrier C, as clearly shown in Figure 3, tension springs E³ acting between lugs E⁴ on the carrier C and lugs E⁵ on the slide B, so that the carrier C is urged towards the rod E¹. The abutment nut E² cooperates with 70 a pin E⁶ carried by the slide B and is normally

locked thereto by a finger screw E⁷, in a manner similar to that described with reference to the abutment nut D.

The carriage C has near one end bearings F² for a vertical shaft F¹ carrying a work table F, and near the other end a bearing G³ carrying a tubular member G² whose upper end is screw-threaded to receive a tube G¹ for supporting a translucent screen G and for enclosing a projection lens G⁴ in a mount G⁵. A light rigid framework H¹ extends downwards from the tubular member G² to support a copy table H for carrying a drawing or other copy whose profile is to be reproduced on the work, the table H being carried by a spindle H² in screwthreaded engagement with the base of the framework H¹ so that the table can be adjusted vertically to and from the lens G⁴ by rotating the table H and spindle H². For the purpose of illuminating the copy, lamps H³ are mounted around the inside of the framework H¹, these lamps being supplied with current through slip rings H⁴ (Figure 4) carried by the framework H¹ and cooperating with spring-loaded brushes H⁵ mounted in a casing H⁶ carried by a part of the fixed base A. Figure 5 shows an alternative arrangement in which a light framework H⁷, corresponding to the framework H¹ described above, carries a translucent table H⁸ which lies above a diffusing screen H⁹ arranged over fixed lamps arranged within a stationary casing H¹⁰.

The projection lens G⁴ projects on the screen G a reduced image of the copy supported on the table H or H⁸, the reproduction ratio being variable in Figure 3 by adjusting the table H and lens mount G⁵, and in Figure 5 by adjusting the lens mount alone.

The tubular member G² has formed thereon a gear wheel F³ equal in size to a gear wheel F⁴ which rotates with the work table F, these two 40 gear wheels being interconnected through an idler gear wheel F⁵ journaled in the carriage C. Rotary movement is thus transmitted between the gear wheels F³ and F⁴ at unity gear ratio so that movement of the work table F, both rotational and translational, are exactly equal to those of the image on the screen G.

Two microscopes J and J¹ (Figure 1) are mounted with their optical axes O, O¹ vertical on a bracket J² carried by the base A, the distance 50 between the two optical axes, O, O¹ being exactly equal to the distance between the axes of rotation R and R¹ of the work table F and the tubular member G² carrying the screen G, lens G⁴ and copy table H, whilst the plane containing the optical axes O, O¹ (the "primary" plane) is parallel to that containing the two axes R, R¹ in all positions of the sliding carriage C since this is constrained, by the mutually perpendicular slideways, to remain parallel to itself.

The tool, which in the construction shown consists of a grinding wheel K, is mounted on a horizontal shaft K¹ parallel to the primary plane and driven through a chain or toothed gearing from an electric motor K². A casing K³ carrying the shaft K¹ and motor K² is mounted on the head of a plunger (not shown) which is reciprocated in a cylinder forming part of a cross slide K⁴ which can be adjusted on the slideway K⁵ by means of a hand wheel K⁶ in a direction at right angles to the primary plane in order to enable the grinding wheel K to be maintained with its operative point exactly in the primary plane beneath the work microscope J, and thereby to allow for wear of the wheel K. The slideway K⁵ is car-

ried on a plate K⁷ which can be turned, by means of a hand wheel K⁸, about a horizontal axis passing through the operative point of the grinding wheel K. Thus, by releasing the plate K⁷ and turning the hand wheel K⁸ the direction of upward reciprocation of the plunger for moving the grinding wheel can be inclined to the vertical at any desired angle for imparting a rake to the work, the plate K⁷ being then clamped in the position of adjustment.

The work table F is also furnished with a worm wheel L³ which is engaged by a worm L² operated by a hand wheel L. Synchronous rotation of the work table F and the tubular member G² can thus be produced by rotating the hand wheel L, a turret lock L⁴ being provided for locking an eccentric sleeve, in which the shaft of the worm L² is journaled, against unintentional rotation into or out of engagement. The worm L² can be thrown out of engagement with the worm wheel L³ by operating a release button L⁵ to turn the eccentric sleeve, for the purpose hereinafter described.

In operation the grinding wheel K is set by means of the hand wheel K⁶ with its operative point on the optical axis O of the work microscope J, and the carriage C is moved by adjustment of the heads D and E to cause the copy microscope J¹ to traverse the outline of the image on the screen G, the grinding wheel being at the same time rotated and reciprocated thus ensuring that the wheel K will grind the work exactly in accordance with the outline of the image and, since the image is itself a scale reproduction of the copy, also in accordance at the appropriate ratio with the outline of the copy. Synchronous rotation of the work table F and screen G by means of the hand wheel L enables grinding to be carried out on all sides of the work and also to be carried out at the angle to the work surface most suitable for grinding.

The machine is preferably provided with means whereby straight lines and circular arcs can be ground on the work in accordance with basic measurements independently of the outline of the copy itself. To this end, in the construction shown, for straight line grinding the work table F is rotated by the hand wheel L to the appropriate orientation, as read off a vernier scale L⁶, relative to the primary plane. The slide B is also adjusted by means of the head D to a position such that the axis of the work shaft F is at the appropriate distance from the primary plane, as read from a vernier scale D⁷. Thus, by manipulation of the head E the carriage C is moved so that the work is ground along the desired straight line, the adjustment of the carriage C along the slideways B³ being indicated on a vernier scale E⁸.

For circular arc grinding the point on the work table constituting the centre of the arc is held fixed at a distance from the operative point of the grinding wheel equal to the radius of the arc. To this end, as shown in Figures 6 and 7, a transverse bridge M⁴ carried by a fixed frame is provided furnished with longitudinal guides M³ for an arm M² which can be traversed along the guides M³ by means of a screw M¹ operated by a hand wheel M. The arm M² carries a pin M⁶ which engages a block M⁸ longitudinally slidable along guides M⁷ formed in a member M⁹ which has an internally threaded central boss so that the member M⁸ can be screwed on to the upper end of the tubular member G² (Figure 3) in place of the tube G¹. The pin M⁶ can thus be

adjusted by the hand wheel M along the guides M⁷ to provide one coordinate for location of the centre of the circular arc to be generated, the pin after final adjustment being locked in position by a stud M⁹ extending through an aperture in a flange carried by the pin M⁶. It will be appreciated that since movements of the table F correspond exactly at unity ratio to those of the tubular member G², and therefore to those of the member M⁸, fixing of the pin M⁶ in any position along the guides M⁷ will be the equivalent of fixing this pin at the corresponding point on the table F. The work table F is provided with apertures N for cooperation with a locking pin N¹ whose head engages a T-slot formed in the gear wheel F⁴ so that the table can be adjusted angularly to give the second coordinate for determining the centre of the circular arc to be generated on the work.

In order to locate the parts accurately in their positions of adjustment, the carriage C is first brought into its zero position with the work and copy axes R and R¹ coincident with the microscope axes O and O¹. The table F is now released from the worm L² by operating the button L⁵, and the locking pin N¹ is also released and the work table F is turned, relatively to the work shaft F, through the appropriate angle (as read from a vernier scale N² provided on the periphery of the work table) constituting one coordinate for determining the centre of the arc to be ground, the table being clamped in the position of adjustment by tightening the locking pin N¹. By means of the hand wheel L, the tubular member G² is turned until the guides M⁷ extend at right angles to the primary plane as shown in Figure 7. The pin M⁶ is then adjusted along the guides M⁷ by operating the hand wheel M to bring the pin to the position of the centre of the arc relatively to the copy axis, and the pin is then secured in such position by tightening the stud M⁹. The abutment nut D is now released and the carriage C is moved by manipulation of the hand wheel M, at right angles to the primary plane until the pin M⁶ is brought to a position, as indicated on a vernier scale M¹⁰ on the hand wheel M (in front of or behind its zero position according to whether the arc is to be convex or concave), to correspond to the radius of the arc to be ground. The centre of the arc is thus fixed at the appropriate radius from the operative point of the grinding wheel K so that movement of the carriage C, which will be accompanied by rotation of the work table F, will cause the grinding wheel K to generate the desired arc on the work.

Although it will usually be simpler to employ polar coordinates in the manner above described for locating the centre of the arc, it will be appreciated that the mechanism may be modified to employ Cartesian coordinates, if desired.

In some instances, for example where one side only of the work needs to be ground, the machine may be considerably simplified by fixing the work support and copy support on the carriage instead of mounting them to rotate thereon. One arrangement of this type is shown by way of example in Figure 8, which comprises a slide P which can move on rollers P¹ cooperating with slideways P² carried by the base A, and a carriage Q which can move on the slide P in a direction at right angles to the movement of the slide P, the carriage Q and slide P being controlled in the manner described above in respect of the carriage C and slide B. The carriage Q is provided

at one end with a light framework S for supporting the copy, and a screwthreaded boss S¹ for receiving the tube S² supporting the lens S³ and screen S⁴. The carriage Q carries at its other end a table Q¹ which is rotationally adjustable on the carriage and can be locked in the rotational position by a bolt Q² whose head cooperates with a T-slot Q³ in the carriage Q.

Thus, though the table Q¹ and copy support S¹ are not synchronously rotatable, the movements of the table are still exactly at unity ratio with the movements of the copy so that the grinding wheel K will reproduce the profile of the copy at a scale determined solely by the magnification ratio of the lens system. The rotational adjustability of the table Q¹ is convenient for dealing with certain types of work, for example where a design is repeated several times, and where accurate matching up of mating curves is not of vital importance a design occupying 360° could be generated by the machine.

It will be understood that other forms of parallel motion device may be employed instead of the mutually perpendicular slideways for controlling the movements of the main carriage. For example, the movements of the carrier may be controlled by pivoted links as shown in Figures 9 and 10, in which the carrier T on which the work table T¹, housing T² for the lens and screen, and copy support T³ are mounted to rotate in synchronism as in the constructions above described, is connected through links U, U¹ and V, V¹ to a fixed pillar W, which carries the work and copy microscopes (not shown). The links A and B are of robust construction and the carrier T has a downward extension T⁴ which supports the lower bearing for the work shaft T⁵, so that the links V and V¹ are relieved of all stresses other than direct tensile or compressive stresses and these two links as also an interconnecting tie V² can be of simple construction.

If desired the two microscopes and the tool may be mounted on the main carriage, whilst the axes of the work table and the copy, lens and screen are fixed in position, or alternately the one pair of elements may be mounted on a carriage movable along a fixed slideway and the other pair on a second fixed slideway at right angles to the first.

50. What I claim as my invention and desire to secure by Letters Patent is:

1. In a copying machine, the combination of a tool for operating on the work, a flat copy whose outlines are to be reproduced on the work, relatively movable supports for the tool and the work, two optical systems, having parallel optical axes and respectively serving for projecting a focussed scale image of the copy and for viewing such image, means for imparting relative movement to the image and the viewing optical system in two dimensions corresponding to those of the flat copy and at right angles to the optical axes of the optical systems whereby the viewing optical system can be caused to trace the outlines of the image, and means whereby the relative movement between the viewing optical system and the image causes strictly equal relative movement between the tool and the work supports, the reproduction ratio of the machine thus being determined solely by the magnification ratio of the projecting optical system.

2. In a copying machine, the combination of a tool for operating on the work, a flat copy whose outlines are to be reproduced on the work, relatively movable supports for the tool and the work,

work, an optical system for projecting a focussed scale image of the copy, such optical system being carried together with the copy by one of the said supports so as to be movable therewith, a microscope for viewing the image and carried by the other support so as to be movable therewith, whereby relative movement between the microscope and the image will cause strictly equal relative movement between the tool and the work, and means for imparting relative movement to the supports in two dimensions at right angles to the optical axes of the projecting optical system and of the microscope, the reproduction ratio of the machine thus being determined solely by the magnification ratio of the projecting optical system.

3. In a copying machine, the combination of a tool for operating on the work, an optical system for projecting a focussed scale image of the copy whose outlines are to be reproduced on the work, a microscope for viewing such image, four relatively movable supports respectively for the tool, for the work, for the image and for the microscope, such supports having datum points or origins two of which have normally fixed operative positions whilst the other two are movable, means for imparting relative movement to the image and microscope supports whereby the microscope can be caused to trace the outlines of the image, and mechanism operating at unity ratio for interconnecting the image and microscope supports with the tool and work supports whereby the relative movement between the microscope and the image will cause equal relative movement between the tool and the work and the line joining the two movable datum points or origins will be maintained equal and parallel to the line joining the normally fixed datum points or origins, the reproduction ratio of the machine thus being determined solely in accordance with the optical magnification ratio.

4. The combination with the features set forth in claim 3, of means whereby the two supports having movable datum points or origins can be synchronously rotated about parallel axes passing respectively through such datum points or origins.

5. In a copying machine, the combination of a tool for operating on the work, a flat copy whose outlines are to be reproduced on the work, relatively movable supports for the tool and the work, an optical system for forming a focussed scale image of the copy in a plane parallel to that of the copy, a microscope for viewing such image, means for imparting relative movement to the microscope and the image in two dimensions parallel to the plane of the image whereby the microscope can be caused to trace the outlines of the image, means whereby the relative movement between the microscope and the image causes equal relative movement between the tool and the work the reproduction ratio of the machine being thus determined solely in accordance with the optical magnification ratio, and means for reciprocating the tool in a direction transverse to the planes of the image and the copy.

6. The combination with the features of claim 2, of means for reciprocating the tool on its support in a direction transverse to the directions of the relative movement between the supports.

7. In a copying machine, the combination of a tool for operating on the work, a flat copy whose outlines are to be reproduced on the work, relatively movable supports for the tool and the work, an optical system for forming a focussed scale

image of the copy in a plane parallel to that of the copy, a microscope for viewing such image, means for imparting relative movement to the microscope and the image in two dimensions parallel to the plane of the image whereby the microscope can be caused to trace the outlines of the image, and means whereby the relative movement between the microscope and the image causes equal relative movement between the tool and the work the reproduction ratio of the machine being thus determined solely in accordance with the optical magnification ratio, the tool being in the form of a grinding wheel rotatable about an axis parallel to the planes of the image and the copy.

8. The combination with the features of claim 2, the tool being in the form of a grinding wheel, of means for rotating such grinding wheel about an axis lying in a plane perpendicular to the optical axes of the microscope and the projecting optical system, and means for reciprocating the grinding wheel in a direction transverse to such plane.

9. In a copying machine, in combination, a tool for operating on the work, relatively movable supports for the tool and the work, an optical system for forming an image of the copy whose outlines are to be reproduced on the work, a sighting device for viewing such image, supports for the image and the sighting device, means for imparting relative movement to the image and the sighting device supports whereby the sighting device can be caused to trace the outlines of the image, and mechanism interconnecting the image and sighting device supports with the tool and work supports, the said mechanism operating at unity ratio whereby relative movement of the tool and work supports causes equal relative movement of the said image and sighting device supports the reproduction ratio of the machine being thus determined solely in accordance with the optical magnification ratio, the four supports for the tool, work, image and sighting device having datum points or origins, the sighting device and tool supports being normally fixed whilst the image and work supports are mounted to turn on a carrier movable under constraint which maintains a line joining the origins of the image and work supports always parallel to a line joining the two origins of the sighting device and tool supports, the image and work supports being synchronously rotatable on the carrier about parallel axes passing through the datum points or origins of the image and work supports.

10. In a copying machine, in combination, a tool for operating on the work, relatively movable supports for the tool and the work, an optical system for forming an image of the copy whose outlines are to be reproduced on the work, a sighting device for viewing such image, supports for the image and sighting device, means for imparting relative movement to the image and sighting device supports whereby the sighting device can be caused to trace the outlines of the image, mechanism interconnecting the image and sighting device supports with the tool and work supports, the said mechanism operating at unity ratio whereby relative movement of the tool and work supports causes equal relative movement of the said image and sighting device supports the reproduction ratio of the machine being thus determined solely in accordance with the optical magnification ratio, the four supports for the tool, work, image and sighting device having datum points or origins, and a carrier for two of the said supports and movable under constraint which maintains a line joining the

origins of the said two supports always parallel to a line joining the two origins of the second two supports, the first two supports being synchronously rotatable on the carrier about parallel axes passing through the datum points or origins of the first two supports.

11. In a copying machine, in combination, a tool for operating on the work, relatively movable supports for the tool and the work, an optical system for forming an image of the copy whose outlines are to be reproduced on the work, a sighting device for viewing such image, supports for the image and the sighting device, means for imparting relative movement to the image and the sighting device supports whereby the sighting device can be caused to trace the outlines of the image, and mechanism interconnecting the image and sighting device supports with the tool and work supports, the said mechanism operating at unity ratio whereby relative movement of the tool and work supports causes equal relative movement of the said image and sighting device supports the reproduction ratio of the machine being thus determined solely in accordance with the optical magnification ratio, the four supports for the tool, work, image and sighting device having datum points or origins, the origins of the sighting device and tool supports being normally fixed whilst the image and work supports are mounted to turn on a carrier movable under constraint which maintains a line joining the origins of the image and work supports always parallel to a line joining the two origins of the sighting device and tool supports, the image and work supports being synchronously rotatable on the carrier about parallel axes passing through the datum points or origins of the image and work supports.

12. In a copying machine, in combination, a tool for operating on the work, relatively movable supports for the tool and the work, an optical system for forming an image of the copy whose outlines are to be reproduced on the work, a sighting device for viewing such image, supports for the image and sighting device, means for imparting relative movement to the image and sighting device supports whereby the sighting device can be caused to trace the outlines of the image, mechanism interconnecting the image and sighting device supports with the tool and work supports, the said mechanism operating at unity ratio whereby relative movement of the tool and work supports causes equal relative movement of the image and sighting device supports the reproduction ratio of the machine being thus determined solely in accordance with the optical magnification ratio, the four supports for the tool, work, image and sighting device having datum points or origins, a movable carrier for two of the said supports, and mutually perpendicular slideways controlling the movements of the carrier and maintaining a line joining the origins of the two supports mounted on the carrier parallel to a line joining the two origins of the second two supports, the first two supports being synchronously rotatable on the carrier about parallel axes passing through the datum points or origins of the first two supports.

13. In a copying machine, in combination, a tool for operating on the work, relatively movable supports for the tool and the work, an optical system for forming an image of the copy whose outlines are to be reproduced on the work, a sighting device for viewing such image, supports for the image and the sighting device, means for

- imparting relative movement to the image and the sighting device supports whereby the sighting device can be caused to trace the outlines of the image, mechanism interconnecting the image 5 and sighting device supports with the tool and work supports, the said mechanism operating at unity ratio whereby relative movement of the tool and work supports causes equal relative movement of the said image and sighting device 10 supports the reproduction ratio of the machine being thus determined solely in accordance with the optical magnification ratio, the four supports for the tool, work, image and sighting device having datum points or origins, the origins of 15 the sighting device and tool supports being normally fixed whilst the image and work supports are synchronously rotatable on a carrier about parallel axes passing through the datum points or origins of the image and work supports, and 20 mutually perpendicular slideways controlling the movements of the carrier and maintaining a line joining the origins of the image and work supports always parallel to a line joining the two origins of the sighting device and tool supports. 25 14. In a copying machine, in combination, a tool for operating on the work, relatively movable supports for the tool and the work, an optical system for forming an image of the copy whose outlines are to be reproduced on the work, 30 means for varying the optical magnification ratio, a sighting device for viewing such image, means for imparting relative movement to the image and the sighting device whereby the sighting device can be caused to trace the outlines of the image, and means whereby relative movement 35 of the tool and work supports causes equal relative movement of the said image and sighting device the reproduction ratio of the machine being thus determined solely in accordance with the optical magnification ratio. 40 15. In a copying machine, in combination, a tool for operating on the work, relatively movable supports for the tool and the work, an optical system for forming an image of the copy 45 whose outlines are to be reproduced on the work, means for varying the optical magnification ratio, a sighting device for viewing such image, supports for the image and the sighting device, means for imparting relative movement to the 50 image and the sighting device supports whereby the sighting device can be caused to trace the outlines of the image, mechanism interconnecting the image and sighting device supports with the tool and work supports, the said mechanism 55 operating at unity ratio whereby relative movement of the tool and work supports causes equal relative movement of the said image and sighting device supports the reproduction ratio of the machine being thus determined solely in accordance with the optical magnification ratio, the 60 four supports for the tool, work, image and sighting device having datum points or origins, the origins of the sighting device and tool supports being normally fixed whilst the image and work 65 supports are synchronously rotatable on a carrier about parallel axes passing through the datum points or origins of the image and work supports, and mutually perpendicular slideways controlling the movements of the carrier and maintaining a 70 line joining the origins of the image and work supports always parallel to a line joining the two origins of the sighting device and tool supports. 75 16. In an engraving machine or the like, means for generating a straight line on the work, comprising in combination, a tool for operating on

the work having a datum point or origin normally lying in a primary plane, a work support, mechanism controlling movement of the work support respectively at right angles to and parallel to the said primary plane, means for rotationally adjusting the work support in accordance with a basic measurement into a determined orientation with respect to the primary plane, means for clamping the work support in the rotational position of adjustment, means for adjusting the work support in accordance with another basic measurement in a direction at right angles to the primary plane and locking the support at a determined distance from the primary plane, and means for moving the work support in a direction parallel to the primary plane relatively to the tool which is thus caused to generate a straight line on the work. 10 15

17. In a copying machine the combination with the features claimed in claim 3, of means for angularly adjusting the work support in accordance with a basic measurement into a determined orientation with respect to the line joining the origins of the tool and sighting device supports, means for clamping the work support in the rotational position of adjustment, means for adjusting the work support in accordance with another basic measurement towards or away from the said line and locking the work support at a predetermined distance therefrom, and means for moving the work support in a direction parallel to said line relatively to the tool which is thus caused to generate a straight line on the work. 20 25 30

18. In an engraving machine or the like, means for generating a circular arc on the work, comprising in combination, a tool for operating on the work, relatively movable supports for the tool and the work, a table carried by the work support, a third support, the tool, work and third supports having datum points or origins, a carrier upon which the work support and third support are mounted to rotate in synchronism about parallel axes passing through their datum points or origins, mechanism controlling the movement 40 of the carrier respectively at right angles to and parallel to a primary plane containing the origin of the tool support, means for angularly adjusting the work table on its support in accordance with a basic measurement constituting one coordinate for locating the centre of the arc to be generated on the work, means for locking the work table on its support in the position of adjustment, means for adjusting the carrier to or from the primary plane in accordance with the 45 radius of the arc to be generated, means for clamping the carrier in the said position of adjustment, a guide member carried by the third support, a follower adjustable along the guide member in accordance with a basic measurement constituting the second coordinate for locating the said centre, and means for locking the follower in the said position. 50 55 60

19. In a copying machine, the combination with the features claimed in claim 9, of a guide member which can be mounted on the image support with the said guide member extending through the origin of the image support, a follower for engaging the guide member on the image support, means for turning the work support relatively to the image support in accordance with a basic measurement constituting one coordinate for locating the centre of the arc to be generated, means for moving the work support and image support towards or away from a pri- 70 75

mary plane containing the origin of the tool support, means for adjusting the follower in the guide member at a distance from the primary plane in accordance with a second basic measurement constituting the second coordinate for locating the said centre, and means for locking the follower in the said position of adjustment.

20. In a copying machine, in combination, a tool for operating on the work, relatively movable supports for the tool and the work, an optical system for forming an image of the copy whose outlines are to be reproduced on the work, a sighting device for viewing such image, means for imparting relative movement to the image and 10 the sighting device whereby the sighting device can be caused to trace the outlines of the image, means whereby relative movement of the tool and work supports causes equal relative movement of the said image and sighting device the 15 reproduction ratio of the machine being thus determined solely in accordance with the optical magnification ratio, means whereby the relative movement between the tool and work supports 20 can be constrained to take place in a straight line, means for effecting relative rotational adjustment through a measured angle between such straight line and the work, and means for effecting relative translational adjustment through a 25 measured distance between such straight line and the work, whereby the tool can be caused to 30 generate a straight line on the work in accordance with basic measurements.

21. In a copying machine, in combination, a tool for operating on the work, relatively movable supports for the tool and the work, an optical system for forming an image of the copy whose outlines are to be reproduced on the work, a sighting device for viewing such image, means for imparting relative movement to the image 35 and the sighting device whereby the sighting device can be caused to trace the outlines of the image, means whereby relative movement of the tool and work supports causes equal relative movement of the said image and sighting device the 40 reproduction ratio of the machine being thus determined solely in accordance with the optical magnification ratio, and means for causing the tool to generate a circular arc on the work in accordance with basic measurements, such 45 means comprising adjusting means for locating on the work by coordinate measurement the point constituting the centre of the arc to be generated, and locking means for holding such point at a measured distance from a datum 50 point on the tool support and thereby constraining the relative movement between the tool and work supports.

22. In a copying machine, in combination, a tool for operating on the work, relatively movable supports for the tool and the work, an optical system for forming an image of the copy whose outlines are to be reproduced on the work, a sighting device for viewing such image, supports for the image and sighting device, means 55 for imparting relative movement to the image and sighting device supports whereby the sighting device can be caused to trace the outlines of the image, mechanism interconnecting the image and sighting device supports with the tool and work supports, the said mechanism operating at unity ratio whereby relative movement of the tool and work supports causes equal relative movement of the image and sighting device sup-

ports the reproduction ratio of the machine being thus determined solely in accordance with the optical magnification ratio, the four supports for the tool, work, image and sighting device having datum points or origins, a movable carrier for two of the said supports and a parallel linkage controlling the movements of the carried and maintaining a line joining the origins of the two supports mounted on the carrier parallel to a line joining the two origins of the second two supports, the first two supports being synchronously rotatable on the carrier about parallel axes passing through the datum points or origins of the first two supports.

23. In an engraving machine or the like, means 15 for generating a circular arc on the work, comprising in combination, a tool for operating on the work, relatively movable supports for the tool and the work, a table carried by the work support, a third support, the tool, work and third 20 supports having datum points or origins, a carrier upon which the work support and third support are mounted to rotate in synchronism about parallel axes passing through their datum points or origins, two mutually perpendicular slideways 25 controlling the movement of the carrier respectively at right angles to and parallel to a primary plane containing the origin of the tool support, means for angularly adjusting the work table on its support in accordance with a basic measurement constituting one coordinate for locating the centre of the arc to be generated on the work, 30 means for locking the work table on its support in the position of adjustment, means for adjusting the carrier to or from the primary plane in accordance with the radius of the arc to be generated, means for clamping the carrier in the said position of adjustment, a guide member carried by the third support, a follower adjustable along the guide member in accordance with a 35 basic measurement constituting the second coordinate for locating the said centre, and means for locking the follower in the said position.

24. In an engraving machine or the like, means 40 for generating a circular arc on the work, comprising in combination, a tool for operating on the work, relatively movable supports for the tool and the work, a table carried by the work support, a third support, the tool, work and third supports having datum points or origins, a carrier upon 45 which the work support and third support are mounted to rotate in synchronism about parallel axes passing through their datum points or origins, a parallel linkage controlling the movement of the carrier respectively at right angles to and parallel to a primary plane containing the origin of the tool support, means for angularly adjusting the work table on its support in accordance with a basic measurement constituting one coordinate for locating the centre of the arc to be 50 generated on the work, means for locking the work table on its support in the position of adjustment, means for adjusting the carrier to or from the primary plane in accordance with the radius of the arc to be generated, means for 55 clamping the carrier in the said position of adjustment, a guide member carried by the third support, a follower adjustable along the guide member in accordance with a basic measurement constituting the second coordinate for locating the said centre, and means for locking the follower in the said position.

MARK HERSCHEL TAYLOR.

CERTIFICATE OF CORRECTION.

Patent No. 2,206,587.

July 2, 1940.

MARK HERSCHEL TAYLOR.

It is hereby certified that error appears in the printed specification of the above numbered patent requiring correction as follows: Page 4, first column, line 45, for the word "alternately" read --alternatively--; page 5, first column, line 50-51, claim 9, for "synchronously" read --synchronous-ly--; page 7, second column, line 7, claim 22, for "carried" read --carrier--; and that the said Letters Patent should be read with this correction there- in that the same may conform to the record of the case in the Patent Office.

Signed and sealed this 3rd day of September, A. D. 1940.

(Seal)

Henry Van Arsdale,
Acting Commissioner of Patents.
